(57) **CLAIM**

The ornamental design for a mobile phone, as shown and described.

DESCRIPTION

FIG. 1 is a front perspective view of a mobile phone in a folded state showing my design.

FIG. 2 is a rear perspective view of the mobile phone in FIG. 1.

FIG. 3 is a front elevation view of the mobile phone in FIG. 1.

FIG. 4 is a rear elevation view of the mobile phone in FIG. 1.

FIG. 5 is a left side elevation view of the mobile phone in FIG. 1.

FIG. 6 is a right side elevation view of the mobile phone in FIG. 1.

FIG. 7 is a top plan view of the mobile phone in FIG. 1.

FIG. 8 is a bottom plan view of the mobile phone in FIG. 1.

FIG. 9 is a front perspective view of the mobile phone in FIG. 1, shown in an unfolded state.

FIG. 10 is a rear perspective view of the mobile phone in FIG. 9.

FIG. 11 is a front elevation view of the mobile phone in FIG. 9.

FIG. 12 is a rear elevation view of the mobile phone in FIG. 9.

FIG. 13 is a left side elevation view of the mobile phone in FIG. 9.

FIG. 14 is a right side elevation view of the mobile phone in FIG. 9.

FIG. 15 is a top plan view of the mobile phone in FIG. 9; and,

FIG. 16 is a bottom plan view of the mobile phone in FIG. 9.

The broken lines in the drawings show portions of the mobile phone that form no part of the claimed design.

1 Claim, 16 Drawing Sheets
